UNITED STATES PATENT OFFICE

169,800

PORTABLE HOT-AIR HEATER

Charles R. Burgess, Detroit, Mich.

Application February 12, 1953, Serial No. 23,590

Term of patent 14 years

(Cl. D81—10)

To all whom it may concern:

Be it known that I, Charles R. Burgess, a citizen of the United States of America, residing at Detroit, in the county of Wayne and State of Michigan, have invented a new, original, and ornamental Design for a Portable Hot-Air Heater, of which the following is a specification, reference being had to the accompanying drawings, forming a part hereof.

Fig. 1 is a perspective view showing the top, front, and one side of the heater and showing my new design.

Fig. 2 is an elevational view of the heater taken from the side shown in Fig. 1.

Fig. 3 is a front elevational view of the heater.

Fig. 4 is a rear elevational view of the heater.

I claim:

The ornamental design for a portable hot-air heater, as shown.

CHARLES R. BURGESS.
